LOUIS H. THULLEN, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

SIGNALING SYSTEM FOR RAILWAYS.

1,109,881.

Specification of Letters Patent.

Patented Sept. 8, 1914.

Application filed August 22, 1904. Serial No. 221,773. Renewed March 5, 1906. Serial No. 304,262.

To all whom it may concern:

Be it known that I, Louis H. THULLEN, a citizen of the United States, formerly residing at Edgewood Park, in the county of Allegheny and State of Pennsylvania, but now residing at Cincinnati, in the county of Hamilton and State of Ohio, have invented certain new and useful Improvements in Signaling Systems for Railways, of which the following is a specification.

My invention relates to signaling systems for railways and particularly to such systems as are applied to electric railways.

I will describe a signaling system embodying my invention and its application to an electric railway and then point out the novel features thereof in claims.

In the accompanying drawings, Figure 1 is a diagrammatical representation of a portion of an electric railway and a signaling system embodying my invention applied thereto. Fig. 2 is also a diagrammatical view, but illustrating another form of my invention.

Referring now to the drawings A designates a portion of a railway in which each of the opposite lines of rails a, a' , are arranged as in the ordinary electric railway. That is, the adjacent rail lengths or sections comprised in each line of rails are mechanically connected together by means of rail joints such as are commonly used for this purpose. The adjacent rail lengths or sections comprised in each line of rails are also connected together electrically by means of copper bonds (of a form usually employed for this purpose) so that the electric current employed for propelling the cars or trains along the railway may flow freely along the lines of rails in its return to the generator. The controlling signaling current applied to the track rails at intervals, can by reason of the electrical connections between adjacent rail lengths or sections, also flow in the two lines of rails. It will be noted that in my invention the usual insulated joints which have been employed to form the "block sections" are omitted.

B designates a generator, which may be a direct current generator or an alternating current generator as desired, for generating current for the propulsion of cars or vehicles along the railway. One pole of the generator is connected in the usual manner with a line conductor f along which travel

the trolleys or shoes w carried by the cars or vehicles.

W is an arbitrary representation of a car or vehicle. The other pole of the generator B is connected with the track rails in the usual or ordinary manner. As shown, it is connected with a cross bond b^2 shown in the form of an inductive winding which in turn is connected with both track rails. Both track rails are used as part of the return path for the propulsion current and each track rail presents substantially the same ohmic resistance to the propulsion current. However, to compensate for any differences in ohmic resistance to the propulsion current and to have the propulsion current potential evenly balanced, as far as practicable, at all points along the railway, cross-bonds E, E' , etc., are employed at different points. Preferably the cross bonds are in the form of inductive windings and so constructed as to present little or no ohmic resistance to the propulsion current while at the same time to present a path of high impedance to any alternating current that may be impressed upon the track rails for signaling purposes. With this arrangement of the track rails the propulsion current will flow through the rails to the generator in preference to flowing through any other path owing to the fact of the track rails presenting a path of low ohmic resistance.

F designates an alternating current generator, and f, f' feeder conductors extending therefrom and along the line of railway.

G, G' , etc., designate transformers located at different points along the railway. The primary windings of the transformers are in circuit with the feeders f, f' and their secondary windings are in multiple circuit with the opposite lines of rails of the railway as clearly shown in the drawing. The location of the transformers is conditional only in so far as the length of the blocks are concerned and the resistance afforded by the apparatus employed in the signaling system. Preferably a transformer should be located approximately midway of two signaling points and preferably at the terminals of the secondary windings of each transformer an inductive winding should be placed.

The distance between signaling points may be of any length, this being determined by existing conditions on a railway, and the

distance between two signaling points may be termed a "block section." In the drawing I have shown three railway signals S, S¹ and S². The distance between the railway signals S, S¹ constitutes one "block section" and the distance between railway signals S¹, S² constitutes another "block section," and so on throughout the length of the railway. The transformer G is shown 10 as being located substantially midway of the ends of the "block section" between railway signals S and S¹, and the transformer G¹ at substantially midway of the ends of the "block section" between railway signals S¹ and S². Each transformer will supply alternating current in both directions toward the ends of its "block section" and each transformer will supply the same alternating current potential at the points of their connection with the rails. This alternating current potential will vary at different points according to the distance from the point of connection of the transformer. This is due to the impedance of a conductor to an alternating current, and this impedance is caused by self-induction, "skin effect" and the "capacity" of the rails. By "skin effect" I mean the tendency of alternating current to traverse the surface of conductors of magnetizable material such as track rails. Each transformer then will furnish to its block section throughout the length thereof an alternating current potential sufficient to operate every translating device or relay connected 20 with the rails of its block section, and it is probable that the point on the track rails midway between any two transformers will be at the minimum alternating current potential, provided no car or vehicle is traveling along the railway. Preferably the railway signals will be located at these points.

Each "block section" is preferably provided with a plurality of translating devices or relays R, R¹, R² and R³, etc., the number 30 depending on the length of the "block section." At least two relays will be employed for each "block section." Whatever the number, that is, more than two, there will be one relay located near each end of each block section. Each translating device will preferably be of such construction as to respond in its control of a railway signal only to the alternating signaling current. The form of translating device or relay illus- 40 trated and described in my Patent No. 823,086 issued June 12, 1906, may be employed. The functions of the several translating devices are the same as in ordinary signaling systems, that is, they act to open or 50 close a signal circuit through their armatures, which armatures therefor constitutes circuit breakers and makers according to the position of a car or vehicle. The signal circuit includes an electrically operated controlling device for a railway signal operat-

ing mechanism. In the drawings the action of the translating devices is such that, when no car or vehicle is in a "block section" in which they are included, they will close through their armatures or circuit-breakers 70 the signal circuit or the "local circuit," as it is generally known in the art, and the signal device of the railway signal will indicate "clear" or "safety." When a car or vehicle is in a "block section" it opens the signal 75 circuit and the signal device will indicate "danger" or "caution." The signal devices of the railway signals may be operated on any of the well known plans, to wit: "normal clear," "normal danger" or variations 80 of these plans, all of which are well known.

Each of the railway signals comprises a signal device which by its color or position relatively to its support gives indications of the service condition of the section of track 85 which it governs or controls and an operating mechanism which is automatically or manually operated and which preferably comprises some electrically operated controlling device which latter is controlled 90 from the "local circuit."

In Figs. 1 and 2 of the drawings, I have shown four translating devices for each "block section" which control the signal circuit for that "block section." Starting 95 from the source of current X, which may be any desired, but here shown as a battery, the signal circuit for the "block section" between railway signals S and S¹ may be traced as follows: wire 1, operating mechanism of railway signal S, wire 2, circuit breaker or armature of translating device R, wire 3, circuit breaker or armature of translating device R¹, wire 4, circuit-breaker or armature of translating device R² (if no car 100 or vehicle were in the "block section"), wire 5, circuit breaker or armature of translating device R³ and wire 6 back to battery. The signal circuit for the "block section" between railway signals S¹ and S², starting 110 from the source of current X¹, may be traced as follows: wire 7, operating mechanism of railway signal S¹, wire 8, circuit breaker or armature of translating device R⁴, wire 9, circuit breaker or armature of translating 115 device R⁵, wire 10, circuit breaker or armature of translating device R⁶, wire 11, circuit breaker or armature of translating device R⁷ and wire 12 back to battery.

The operation of the system embodying 120 my invention and as shown and described in Figs. 1 and 2 is as follows: The propulsion current from the generator B will always return from the car or vehicle motors through the track rails, they being electrically connected and bonded so as to present substantially the same ohmic resistance throughout their length. The alternating current which is impressed on or supplied 125 the track rails will be limited in its magnetic 130

or operative effect on the translating devices, to the individual blocks, this being regulated through the capacity of the transformer and the impedance offered by the 5 track rails, this impedance being from 1 to an infinite number of times more than the ohmic resistance of the track rails to the direct current. A car or train traversing the railway will short-circuit one or more translating devices, but will not short circuit all 10 of the translating devices as the alternating current furnished to the "block system" occupied by the car will have a difference of potential between the transformer connections to the track rails and the car, which 15 will be zero at the point where the car is located but will increase toward the point where the secondary winding of the adjacent transformers is connected with the 20 track rails. It can be readily seen that the translating devices, where the car is located will be shunted as the alternating current potential at that point will be zero. Also the translating devices in the immediate vicinity of the car will have a very low alternating current potential at their terminals owing to their proximity to the car. The translating devices farthest from the car 25 will have considerable alternating current potential at their terminals and which will give sufficient current to operate them, and thus have them close the "local circuit" at those points.

As shown in Fig. 2, the system is operated 30 without the back contacts and controlling wires leading therefrom on the translating devices in which case the car would influence the railway signal through the translating devices as it passes along the track as 35 above described. In order to make a close dividing point at the location of the railway signals I have shown (see Fig. 1) the translating devices adjacent to these railway signals with back contacts whereby if one 40 translating device adjacent the railway signal opens the signal circuit it will in turn close the proper contacts of the adjacent translating device which would be on the back contacts at the same time. For example, the translating device R^3 is provided 45 with two back contacts c^1 , c^2 , and the translating device R^4 with two back contacts d^1 , d^2 . As the car W approaches the signal S^1 it will reach a point where it deenergizes R^3 , 50 thereby closing the back contacts c^1 , c^2 , through the armature of R^3 . As the car W advances still farther, it will in like manner deenergize R^4 , thereby causing its armature to drop and opening the local circuit of the 55 signal S^1 at that point. This would have the effect of causing the signal S^1 to assume the danger position before the car W had reached it, were it not for the fact that the local circuit of S^1 has already been closed 60 through the back contacts of R^3 , which acts

as a shunt circuit to the front contacts of R^4 . As soon as the car W has passed the signal S^1 , the relay R^3 will again become energized by current flowing from the source G, and the back contacts c^1 , c^2 , will be 65 opened, thereby opening the local circuit of signal S^1 and causing it to assume the danger position. Therefore it will be seen that a car will short circuit the two translating devices adjacent the railway signal but will 70 only open the signal circuit of one railway signal. This same idea could be carried out through several translating devices if desired. It depends altogether on the distances apart at which the translating devices 75 are connected, the adjustment of the translating devices and the amount of drop along the track and E. M. F. at the transformer.

No broad claim is made herein for a track circuit in which the source of signaling current is located at about the middle of the track circuit and with a relay or translating device located at about each end of the track circuit, as this forms the subject-matter of my co-pending application which was originally filed August 22, 1904, renewed February 27, 1906, with Serial No. 303,201.

Having thus described my invention, what I claim is:

1. The combination with an electric railway system which comprises a source of current of one character, a circuit therefor comprising two sides, one of which is formed by both track rails of the trackway and which are without insulated joints where a 95 signaling system is applied, and vehicles propelled along the railway by current from said source of power current; of railway signals located at intervals along the trackway and signaling the passage of the vehicles; a signal circuit for each railway signal; a plurality of relays each controlling a circuit breaker in said signal circuit, a relay being at each end of the signal circuit and connected with the track rails; and a 100 source of controlling signaling current for supplying an alternating signaling current to the plurality of relays, said source of controlling current being connected with both track rails and located intermediate the 105 relays at the ends of the signal circuit.

2. The combination with an electric railway system which comprises a source of current of one character, a circuit therefor comprising two sides, one of which is formed by both track rails of the trackway and which are without insulated joints where a signaling system is applied, and vehicles propelled along the railway by current from said source of power current; of railway signals located at intervals along the trackway and signaling the passage of the vehicles; a signal circuit for each railway signal comprising a wire independent of the trackway and extending along the track- 115

way; a plurality of relays each controlling a circuit breaker in said signal circuit, a relay being at each end of the signal circuit and the relays connected with the track rail; and a source of controlling signaling current for supplying an alternating signaling current to the plurality of relays, said source of controlling current being connected with both track rails and located intermediate the relays at the ends of the signal circuit.

3. The combination with an electric railway system which comprises a source of power current of one character, a circuit therefor comprising two sides, one of which is formed by both track rails of the trackway and which are without insulated joints where a signaling system is applied, and vehicles propelled along the railway by current from said source of power current; of railway signals located at intervals along the trackway and signaling the passage of the vehicles; a signal circuit for each railway signal extending along the trackway; a plurality of relays each controlling a circuit breaker in said signal circuit, a relay being at each end of the signal circuit and the relays connected with the rails of the trackway; a source of controlling signaling current for supplying an alternating signaling current to the plurality of relays, said source of controlling current being connected with both track rails and located intermediate the relays at the ends of the signal circuit; and bonds placed across the rails of the trackway at intervals to equalize any differences of potential of the car propulsion current between the track rails and without short-circuiting the alternating signaling current from the relays.

4. The combination with an electric railway system which comprises a source of current of one character, a circuit therefor comprising two sides, one of which is formed by both track rails of the trackway and which are without insulated joints where a signaling system is applied, and vehicles propelled along the railway by current from said source of power current; of railway signals located at intervals along the trackway and signaling the passage of the vehicles; a signal circuit for each railway signal extending along the trackway; a plurality of relays each controlling a circuit breaker in said signal circuit, a relay being at each end of the signal circuit and the relays being connected with the track rails; and a transformer for each signal circuit located intermediate the relays at the ends of the signal circuit, and having its secondary winding connected with both track rails for supplying an alternating signaling current to the plurality of relays; a main source of alternating signaling current, a conductor

therefrom, to which the primary windings of the several transformers are connected.

5. The combination with an electric railway system which comprises a source of current of one character, a circuit therefor comprising two sides, one of which is formed by both track rails of the railway and which are without insulated joints where a signaling system is applied, and vehicles propelled along the railway by current from said source of power circuit; cross-bonds connecting said rails together at intervals and which do not short-circuit the signal current from the relays, railway signals located at intervals along the railway; a signal circuit for each railway signal extending along the trackway; a plurality of relays for each signal circuit, one being located at each end of each signal circuit and each relay controlling a circuit breaker in its signal circuit and the relays being connected with the track rails; and a source of signal current furnishing controlling energy to the relays of each signal circuit and located intermediate the relays of its signal circuit.

6. The combination with the trackway of an electric railway having its opposite lines of rails electrically continuous for alternating signaling currents and which are without insulated joints where a signaling system is to be applied; a source of power current; a circuit therefor of which the opposite lines of rails form a part; railway signals located along the trackway to form signaling points, the length of track from one railway signal to the next adjacent railway signal constituting a block-section; a source of alternating signaling current for each block-section connected with both rails thereof and located midway of the ends of the block section; a signal circuit for each railway signal extending along the railway; and a relay located at each end of a block-section energized by the alternating signaling current of that block section for moving the armatures thereof, which are included in the signal circuit for the railway signal for that block section and said relays being connected with the track rails.

7. The combination with an electric railway system which comprises a trackway having each line of rails continuous through a succession of blocks, a source of current of one character, a circuit therefor comprising two sides, one of which is formed by both track rails of said trackway, and vehicles propelled along the railway by current from said source of power current; of railway signals located at intervals along the trackway and signaling the passage of the vehicles; a signal circuit for each railway signal; a plurality of relays each controlling a circuit breaker in said signal circuit, a relay being at each end of the signal circuit and connected with the rails of the trackway; a

- source of controlling signaling current for supplying an alternating current to the plurality of relays of each signal circuit, each source of controlling current being connected with both track rails and located intermediate the ends of its signal circuit; and like poles of adjacent sources of controlling signaling current being connected to the same track rail.
10. 8. The combination with an electric railway system which comprises a trackway having each line of rails continuous through a succession of blocks, a source of current of one character for propelling vehicles along the railway, a circuit for said source of current comprising two sides one of which is formed by both track rails of said trackway; of railway signals located at intervals along the trackway and signaling the passage of the vehicles; a signal circuit for each railway signal extending along the trackway; a plurality of relays each controlling a circuit breaker in said signal circuit, a relay being at each end of the signal circuit and the plurality of relays for said signal circuit being connected with the track rails; a source of controlling signaling current for supplying an alternating signaling current to the plurality of relays, said source of controlling current being connected with both track rails and located intermediate the relays at the ends of the signal circuit; and bonds placed across the rails of the trackway at intervals to equalize any differences of potential of the car propulsion current between the track rails and without short circuiting the alternating signaling current from the relays; the relative location of the relays and sources, and the adjustment of the relays and sources relative to the length and impedance of the rails in each block, constituting the means for segregating the adjacent blocks.
15. 9. The combination with an electric railway system which comprises a source of power current of one character, a circuit therefor comprising two sides, one of which is formed by both track rails of the trackway and which are without insulated joints where a signaling system is applied, and vehicles propelled along the railway by current from said source of power current; of railway signals located at intervals along the trackway and signaling the passage of the vehicles; a signal circuit for each railway signal extending along the trackway;
20. a plurality of relays each controlling a circuit breaker in said signal circuit, a relay being at each end of the signal circuit and the plurality of relays for said signal circuit being connected with the track rails; a source of controlling signaling current for supplying an alternating signaling current to the plurality of relays, said source of controlling current being connected with both track rails and located intermediate the relays at the ends of the signal circuit; and bonds placed across the rails of the trackway at intervals to equalize any differences of potential of the car propulsion current between the track rails and without short circuiting the alternating signaling current from the relays; the relative location of the relays and sources, and the adjustment of the relays and sources relative to the length and impedance of the rails in each block, constituting the means for segregating the adjacent blocks.
25. 10. In combination, a trackway comprising two continuous lines of rails which are without insulated joints where a signaling system is applied; a succession of signals located at intervals along the trackway; a signal circuit along the trackway for each signal; a plurality of circuit breakers in each signal circuit one adjacent to each end of its signal circuit; a plurality of relay magnets connected with the rails each for controlling one of said circuit breakers; sources of signaling current, one for each signal circuit, located intermediate the plurality of relays for each signal circuit, connected by both poles to the trackway, and like poles of all sources connected to the same rail; and current paths formed by the wheels and axles of a car traveling along said trackway for maintaining its shunting action on a relay of one signal circuit until it shunts an adjacent relay on the next adjacent signal circuit.
30. In testimony whereof I have signed my name to this specification in the presence of two subscribing witnesses.

A. HERMAN WEGNER.

It is hereby certified that in Letters Patent No. 1,109,881, granted September 8, 1914, upon the application of Louis H. Thullen, of Edgewood Park, Pennsylvania, for an improvement in "Signaling Systems for Railways," errors appear in the printed specification requiring correction as follows: Page 4, line 3, for the word "circuit" read *circuits*; same page, line 5, for the word "rail" read *rails*; same page, line 76, for the word "circuit" read *current*; same page, line 96, strike out the words "to be"; and that the said Letters Patent should be read with these corrections therein that the same may conform to the record of the case in the Patent Office.

Signed and sealed this 17th day of November, A. D., 1914.

[SEAL.]

R. F. WHITEHEAD,

Acting Commissioner of Patents.
